United States Patent Office.

S. R. BAILEY, OF BATH, MAINE.

Letters Patent No. 85,895, dated January 19, 1869.

IMPROVEMENT IN SLEIGHS.

The Schedule referred to in these Letters Patent and making part of the same.

To all to whom these presents shall come:

Be it known that I, S. R. BAILEY, of Bath, in the county of Sagadahoc, and State of Maine, have made an invention of a new and useful Improvement in the Construction of Sleighs; and do hereby declare the following to be a full, clear, and exact description thereof, due reference being had to the accompanying drawings, making part of this specification, and in which—

Figure 1 is a cross-section of the lower part of a sleigh-body and its runners, and

Figure 2 is a perspective view of one of its runner-standards or posts, and a portion of one of its cross-bars, showing the connection of the two.

This invention relates to means for uniting the cross-bars of sleigh-bottoms to the runner-posts or uprights, whereby much greater strength of parts, durability, and elegance of finish are obtained, at no increase of expense as compared with the present construction of such vehicles.

As heretofore constructed, the upper end of the runner-posts has been united to cross-bar, by a mortise and tenon, and the union thus made, stiffened by means of an iron brace, extending angularly between the two. The joint thus made is a source of weakness, and fractures often take place at this point.

My present invention consists in abolishing the tenon and mortise, and, in place thereof, prolonging the upper end of the runner-posts or uprights, in a graceful curve, alongside of the bottom part of the cross-bar, and applying an iron strap or brace to each side of such post, and substantially from end to end thereof, with the exception that the upper end of the outer iron strip diverges from the post, in a curved line, and is joined in any suitable manner to the outer end of the cross-bar, thus serving both as a brace to strengthen these posts, and to give a finished appearance to them.

The opposite side posts of the two runners may be formed of one and the same piece of wood, steamed, and bent into the requisite form, as shown in the accompanying drawings, or they may be in independent pieces, and joined to the under side of the cross-bar, the inner iron strap, in either case, being preferably in one piece.

By means of the above-described construction of

parts, I obtain the advantage, as before premised, of a much stronger and more lasting union of the runner-posts and cross-bars, without an additional expense, as compared with the present construction of sleighs, while I gain an improvement in finish and graceful appearance, which a curved line nearly always presents over an angular one.

The drawings before alluded to represent the side rails of the sleigh-body at *a a*, one of the cross-bars at *b*, and the floor-boards at *c c*, &c.

The runner-posts *d d*, as by my invention, are joined in the ordinary manner, at their lower ends, to the runners *e e*, while their upper portions are secured, as shown at *f*, and carried under and glued or otherwise secured to the cross-bar *b*, at some distance from its outer ends.

A metallic strap or plate, *g*, is secured to the inner side of the runner, and to the inner faces of the posts *d d*, or the face of the bar of wood composing them, while to the outer face of the runner and the posts *d d*, a similar metallic strap, *i* or *i*, is secured.

The upper end of the strap *i*, as before mentioned, diverges in a curved line from the curved corner of the post *d*, and is secured in a suitable manner to the cross-bar *b*, and to the sleigh-body.

This description of the construction of my invention will enable carriage or sleigh-builders to manufacture them.

Claim.

I claim as my invention, and desire to secure by Letters Patent of the United States—

The mode herein described of uniting the posts or standards of sleigh-runners to the bottom of the sleigh, that is, in dispensing with the ordinary tenon and mortise, and prolonging the posts in a curved form, and affixing them to the cross-bars, as herein represented, the tenon thus formed being strengthened by the adoption of the metallic plates *g* and *i*, the whole being combined, applied, and producing results before explained.

S. R. BAILEY.
